(57) CLAIM

The ornamental design for a spinning top, as shown and described.

DESCRIPTION

FIG. 1 is front and slightly top view of a spinning top according to the present invention.

FIG. 2 is a top view of the spinning top depicted in FIG. 1. FIG. 3 is a perspective rear, left side and slightly top view of the spinning top depicted in FIG. 1, the perspective front, right side, and slightly top view being a mirror image thereof.

FIG. 4 is a bottom view of the spinning top depicted in FIG. 1; and,

FIG. 5 is a perspective front, top and right side view of the spinning top depicted in FIG. 1.

No claim is made to either the unshaded areas within the top of the ring shaped base or the unshaded portions within the broken line circle in FIG. 4 that are not visible in FIGS. 1 and 3. The features shown in broken lines are for illustrative purposes only; and likewise form no part of the claimed design.
